CLAIM

The ornamental design for an appliance display screen or portion thereof with graphic user interface, as shown and described.

DESCRIPTION

FIG. 1 is a front view of a first image in a sequence of an appliance display screen or portion thereof with graphic user interface according to the design; and, FIG. 2 is a front view of a second image in the sequence thereof.

The evenly-dashed broken lines depict portions of the graphic user interface that form no part of the claimed design.

Long-short-long-dashed broken lines depict the appliance display screen or portion thereof as well as define the bounds of the claimed design and form no part of the claimed design. The appearance of the graphic user interface sequentially transitions between the images shown in the Figures. The process or period in which one image transitions to another forms no part of the claimed design.
